JULIUS H. BECKER, OF SAN FRANCISCO, CALIFORNIA, ASSIGNOR TO AMERICAN HEAT & POWER CO., OF SAN FRANCISCO, CALIFORNIA, A CORPORATION OF CALIFORNIA.

ADJUSTABLE SUPPORT FOR BURNER-PLATES.

1,114,848.

Specification of Letters Patent.

Patented Oct. 27, 1914.

Application filed February 24, 1913. Serial No. 750,211.

To all whom it may concern:

Be it known that I, JULIUS H. BECKER, a citizen of the United States, residing in the city and county of San Francisco and 5 State of California, have invented new and useful Improvements in Adjustable Supports for Burner-Plates, of which the following is a specification.

This invention relates to an adjustable 10 burner plate for liquid hydrocarbon fuels.

The object of this invention is to provide a simple and durable adjustable burner plate of the type used in down-draft furnaces using liquid hydrocarbon fuels.

15 The invention consists of the parts and the construction and combination of parts as hereinafter more fully described and claimed, having reference to the accompanying drawings, in which—

20 Figure 1 is a vertical section of a down-draft furnace showing the application of the burner plate. Fig. 2 is a plan section.

Referring to the drawings, A indicates a base plate suitably mounted or secured in 25 the base portion of a down-draft furnace, generally indicated at B. Centrally formed or otherwise secured upon this plate is a hollow socket member 2, provided with a central opening 3 formed for the purpose of 30 providing a communicating passage between the main combustion chamber 4 and an auxiliary combustion chamber 5.

Loosely mounted upon the socket member 35 is a second socket member 6, which is connected by flanges 7 with a bracket plate 8 provided for the purpose of supporting the main burner plate, indicated at 9. The bracket plate 8, together with the main supporting plate A, may be made of cast iron 40 or like material, while the burner plate 9 should preferably be made of cast steel or like material which will be able to stand the high temperatures of the furnace without cracking or bending out of shape. This is 45 of great importance when one considers that any slight bending or warping of the plate might cause an uneven flow or discharge of the liquid fuel from the plate with a consequent inequality of flame distribution.

50 In operation, a temporary fire is made from any suitable fuel placed in the auxiliary combustion chamber 5 below the burner plate 9, all draft openings except the door 10 being closed. This fire is continued until 55 the plate 9 becomes sufficiently heated to

vaporize water and oil delivered to the plate. Oil and water in the right proportions are then gradually turned on and are ignited by the flames discharging around the edge of the plate 9 from the lower auxiliary combustion chamber 5. The ribs or flanges 7, connecting the bracket plate 8 with the socket member 6, are so positioned as to form passages 11 through which the flames from the auxiliary combustion chamber 60 may discharge.

The moment sufficient heat has been generated within the main combustion chamber to support combustion, the fire within the temporary or auxiliary heating chamber 5 65 may be drawn and the door 10 closed. The main draft necessary for combustion is then admitted, together with the falling fuel mixture, through a central opening 12. The fall of the mixed oil and water from the 70 conveying pipe 12^a is sufficient to cause it to spatter and atomize. The mixture is thus evenly spread over the plate and burns with a flame which spreads to all sides of the combustion chamber.

80 From the above description it can easily be seen that the adjustable mounting of the burner plate 9, with relation to the main supporting base A, is of great importance. Any settling of the brick work of the furnace would otherwise disturb the level of the plate and cause an uneven flow of fuel from the plate with a consequent poor distribution of fuel from the plate.

85 The plate mounting here shown is simple 90 and substantial in construction and may be easily adjusted at any time without shutting down the furnace or disturbing the fire in any way, as the plate may be easily adjusted at any time through the central opening 12 by the aid of a rod or similar means by which the plate may be slightly tapped to adjust its level. The oil discharged from the plate acting as a level will immediately indicate the amount of adjustment necessary. 100 The burner plate being mostly subjected to the high temperatures of the combustion chamber may be renewed and replaced at any time without disturbing the adjustable mounting on which it is supported.

105 The materials and finish of the several parts of the device are such as experience and judgment of the manufacturer may dictate.

I wish it understood that various changes in form and proportions of construction may be resorted to within the scope of the appended claims and that I do not wish to limit myself to the specific design here shown.

Having thus described my invention, what I claim and desire to secure by Letters Patent is—

- 10 1. An adjustable support for burner plates comprising in combination, a base plate, a hollow socket member having a central opening, formed on said plate, an adjustable support mounted on the socket member, and
- 15 2. An adjustable support for burner plates

comprising in combination, a base plate, a hollow socket member having a central opening formed on said plate, a second socket member having a series of radially extending arms upon which is secured an open bracket plate and mounted on said first-named socket member, and a burner plate carried by said open bracket plate.

In testimony whereof I have hereunto set 25 my hand in the presence of two subscribing witnesses.

JULIUS H. BECKER.
